DESIGN FOR A DISPLAY CONTAINER

Jean O. Reinecke, Oak Park, Ill., assignor to
Lactona Incorporated, St. Paul, Minn.

Application June 20, 1947, Serial No. 139,838

Term of patent 3½ years

(Cl. D80—5)

To all whom it may concern:

Be it known that I, Jean O. Reinecke, a citizen of the United States and a resident of Oak Park, county of Cook, and State of Illinois, have invented a new, original, and ornamental Design for a Display Container, of which the following is a specification, reference being had to the accompanying drawing, forming part thereof.

Figure 1 is a perspective view of a display container, showing my new design;

Figure 2 is a plan view of the bottom portion of the same; and

Figure 3 is a sectional view through the container, the position of the section being indicated by the line 3—3 of Figure 2.

I claim:

The ornamental design for a display container, as shown.

JEAN O. REINECKE.
